Filed Dec. 29, 1958, Ser. No. 783,562

5 Claims. (Cl. 128—304)

This invention pertains to surgical devices and more particularly to an arrangement for treating arteriosclerotic occlusive disease.

In the past in treating occluded arteries the approach generally has been either to provide an arterial graft, or to restore the living artery by means of conventional endarterectomy. The former expedient requires a supply of vessels for use in the operation and the results have been indeterminate and inconclusive as to the benefit obtained. On the other hand, removal of the occlusion from the living artery has been a long and difficult operation, unsuitable for persons in advanced age groups. It has been necessary to make a longitudinal incision in the artery throughout the entire length of the obstruction. This may extend for as much as 32 centimeters, and in some instances even longer. After removal of the obstructing intima and secondary thrombus, the entire incision must be closed by a running arterial suture. It is necessary to do this very meticulously which extends the operating time to what may be unacceptable limits.

According to the present invention, an instrument is provided giving the advantages of freeing a living artery, yet drastically reducing operating time.

Therefore, it is an object of this invention to provide an instrument usable in treatment of arteriosclerotic occlusive disease.

Another object of this invention is to remove an obstruction in an artery without extensive suturing.

A further object of this invention is to materially reduce operating time in the treatment of such cases.

Yet another object of this invention is to provide an instrument having a short tubular cutting portion on the end of a flexible handle which may be inserted within an artery for removing an occlusion therein.

These and other objects will become apparent from the following detailed description taken in connection with the accompanying drawing in which:

Fig. 1 is a perspective view of the surgical instrument of this invention.

Fig. 2 is an enlarged fragmentary sectional view illustrating the forward cutting portion of the instrument.

Fig. 3 is an enlarged sectional view illustrating a portion of the artery prepared for removal of the occlusion by the instrument of this invention.

Fig. 4 is a fragmentary perspective view of the instrument used in its initial stage in freeing the interior of an artery.

Fig. 5 is an enlarged sectional view showing the instrument of this invention during its removal of an occlusion from within an artery, and

Fig. 6 is an elevational view, partially broken away, of a modified form of flexible handle for the instrument of this invention.

Referring to the drawing, and in particular to Figs. 1 and 2, instrument 1 of this invention is provided with a flexible handle 2, one end of which carries a cutting member 3. The latter is constructed from a section of thin wall tubing cut to provide parallel front and back faces

2

4 and 5 which are inclined with respect to the axis of the tube. In the preferred embodiment these faces are arranged so that angle α at the forward edge of the tubular section is 20° . Angle β between the axis A of tubular member 3 and front face 4 therefore is 70° . Outer periphery 6 of the tubular section tapers forwardly toward face 4 so as to define a relatively sharp cutting edge at this face. Interior surface 7 may remain parallel to the axis of the tubular section.

10 Tubular section 3 and handle 2 are both constructed of stainless steel for durability and corrosion resistance. The joint between the handle and the tubular section is accomplished by silver soldering end 8 of the handle to face 5 in alignment with outer surface 7. The attachment of the tubular section to the handle is such that cutting face 4 inclines from end 8 of the handle. This positions the forward portion 9 of face 4 of the tubular section diametrically opposite the connection of the handle to member 3.

20 In using the instrument of this invention the patient is placed supine under a long-acting spinal anesthesia. An incision is made and the artery is isolated. It is explored for collapsibility and opened to check for adequate back flow from below as a result of filling from adequate 25 collateral. It is preferred also to obtain a popliteal arteriogram in order to ascertain the exact status of the vessel. If the popliteal artery is patent and is continuous with at least one major branch vessel, it is desirable to continue with the operation.

30 It is important in the next phase of the operation to start the cleavage plane properly between the thickened intima and the surrounding media. Thus, as seen in Fig. 3, a beveled cut 10 is made in loosening intima 11 from the interior of artery 12 at the location of short 35 longitudinal incision 13. This prevents subsequent dissection of the distal intimal edge when blood flow is re-established. After this beveled incision has been accomplished carefully around the entire inner circumference of the artery, instrument 1 is threaded on intima 11 in

40 the manner illustrated in Fig. 4. The intima is received by the interior of tubular member 3 with cutting face 4 at the forward edge toward the occluded section of the artery. Instrument 1 then is advanced from incision 13 as best seen in Fig. 5 which frees the thickened intima 45 from the arterial wall. Tubular section 3 is gently forced forwardly by handle 2 extending through incision 13 into the artery a distance sufficient to free the entire obstruction portion. The substantially 70° inclination of the cutting face has been found to give optimum results 50 in advancing the cleavage plane. Other angular relationships may be used successfully if not as effectively.

55 When the occluding portion has been freed by the instrument of this invention, it may be pulled from the artery through incision 13, following which the instrument also is removed and the necessary sutures are made.

It can be seen from the foregoing, therefore, that it is possible by the use of the instrument of this invention to remove a lengthy obstruction from within an artery while making only a small incision in the wall of the 60 artery. It is a comparatively simple matter to advance the instrument through the artery for freeing the obstructing core, and very little suturing is required. This means that operating time is greatly reduced and that improved results are obtained.

65 The instrument of this invention may be made in various sizes so that arteries of different diameters may be successfully operated upon. Preferably a number of instruments of graduated sizes are supplied in a surgical kit so that whatever the size of the vessel encountered 70 a properly dimensioned instrument will be available. The outer diameter of the tubular section may vary considerably from around .110 inch to nearly one-half inch

in size. Similarly, wall thickness may run from .060 inch to .110 inch in typical examples.

The handle for the instrument of this invention may be the single stainless steel wire shown in Figs. 1 and 2, or it may be in the form illustrated in Fig. 6, particularly usable for instruments in the larger sizes. By this construction, central portion 14 is made up of three strands of wire extending in a substantially axial direction but given a slight twist as illustrated. Helically wrapped around the exterior of portion 14 is an additional wire 15 entirely covering the central portion throughout its length. This provides a strong, flexible handle which has some rigidity in the axial direction, but which also will retain a curvature imparted to it.

From the foregoing, therefore, it may be seen that I have provided an improved surgical instrument readily usable in removing arterial obstructions without requiring long operating time or extensive suturing. The instrument is comparatively simple to construct and use, and with the front cutting edge inclined forwardly at approximately 70° as described above, an effective cleavage of the thickened intima is obtained.

The foregoing detailed description is to be clearly understood as given by way of illustration and example only, the spirit and scope of this invention being limited solely by the appended claims.

I claim:

1. A surgical instrument comprising a tubular member one end of which is provided with a wedge-shaped annular cutting edge and inclined with respect to the axis of said tubular member, and a flexible rod-like thrust-absorbing handle attached to the opposite end of said member at one side of the axis thereof so that said inclined edge projects away from said handle, and the aperture through said tubular member is open.

2. A surgical instrument comprising a relatively short tubular member, the outer periphery of said tubular member at one end being tapered inwardly to provide with the inner periphery a cutting edge at said end, said cutting

edge being inclined at an angle of substantially 70° with respect to the axis of said tubular member, and a flexible handle secured to the opposite end of said tubular member.

3. A surgical instrument comprising a relatively short tubular member the ends of which are parallel and inclined with respect to the axis of said member, the outer surface of one end of said member being tapered inwardly to define a cutting edge at said end, and a handle attached to the opposite end of said member so that said cutting edge inclines away from said handle.

4. A device as recited in claim 3 in which said handle comprises a plurality of substantially axially extending wires at the axis of said handle, and a covering over said wires by an additional wire wound helically thereon.

5. A surgical instrument comprising a relatively short thin walled stainless steel tubular member, the ends of said member being parallel and inclined with respect to the axis of said tubular member at an angle of substantially 70°, the inner surface of said tubular member being substantially cylindrical in shape, the outer surface of said tubular member tapering toward said inner surface at one end of said member to define with said inner surface a cutting edge, and a stainless steel wire handle silver soldered to said tubular member in substantial alignment with the outer surface thereof at the end of said tubular member opposite said cutting edge and positioned so that said cutting edge inclines away from said handle.
